J. C. WAHL

MECHANICAL PENCIL

Filed March 28, 1921

UNITED STATES PATENT OFFICE.

JOHN C. WAHL, OF CHICAGO, ILLINOIS, ASSIGNOR TO THE WAHL COMPANY, OF CHICAGO, ILLINOIS, A CORPORATION OF DELAWARE.

MECHANICAL PENCIL.

Application filed March 28, 1921. Serial No. 456,354.

My invention relates to improvements in pencils, and is especially concerned with improvements in that type of pencil which comprises a barrel made of metal or other suitable material having a passage therein for receiving and holding the leads, and suitable means for extruding the end of the lead through one end of the barrel so that it can be used for writing.

10 The objects of my invention are:—

First: To provide a pencil of this character comprising a novel means for extruding or feeding the lead from the end of the pencil, and

15 Second: To provide a pencil of the character described, which is simple of construction, economical to manufacture and easy to operate.

These and other objects will definitely appear as the description progresses, reference being had to the accompanying drawings, in which—

20 Fig. 1 is a longitudinal sectional view of my improved pencil, showing the parts in 25 their assembled position.

Fig. 2 is a fragmentary longitudinal sectional view of my improved pencil showing the propelling mechanism in its operative position.

30 Fig. 3 is a perspective view of that part of the pencil showing the cap and clip attached to the pencil barrel.

Fig. 4 is a disassembled view of some of the parts of the pencil and showing their 35 relation to each other.

Fig. 5 is a cross sectional view on the line 5—5 of Fig. 1, and

Fig. 6 is an assembled view of the feed wire and cross head.

40 With reference to the drawings, 10 indicates an outer barrel or casing swaged as at 11 and forming an aperture in which is inserted the rifled tip 12. Detachably mounted in the interior of the barrel or casing 10 are lead magazines 13 and 14, said magazines being constructed of two lengths of hollow tubing. These lead magazines are held in relation to each other by being soldered to an exteriorly threaded cap 15 and 45 to the plug 16. The threaded cap 15 has two openings therein which are in alignment with the hollow portion of the lead maga-

zines 13 and 14, thus allowing the insertion of extra leads in the magazines or their withdrawal therefrom when desired. 55

An eraser holder, threaded interiorly, and so constructed as to receive an eraser 18, is provided. The interior threads of the eraser holder 17 engage the exterior threads of the cap 15, said eraser holder being knurled in 60 order to form a better gripping surface when it is desired to either propel or repel the lead in the lead guide.

The barrel 10 is threaded interiorly, commencing immediately below the shoulder 37, 65 (see Fig. 4) and inasmuch as said threads engage the teeth in the crosshead 20, as hereinafter described, it is not necessary to extend the threads below that point in the barrel beyond which the said crosshead 20 70 is prevented from going by reason of its contact with the plug 16.

The lead magazines 13 and 14 are so constructed as to form grooves 30 and 31 on the side of the magazines the greatest distance from the barrel 10, as is best shown in Fig. 5. Loosely mounted between the magazines 13 and 14 is a crosshead 20 having teeth 21 which are adapted to engage the threaded interior of the barrel or casing 10. On 80 the face of the crosshead are upstanding lugs 22 which are adapted to ride in the grooves 30 and 31 of the magazines 13 and 14. This arrangement is necessary to prevent the crosshead from falling out of the magazines 85 upon the withdrawal of the said magazines from the pencil barrel. As this arrangement of parts broadly does not in any way form a part of my invention, and as it is more clearly and completely explained in Patent 90 No. 1,130,741 granted to Charles R. Keeran under date of March 9, 1915, it is not believed necessary at this time to incumber this application with a minute detailed description of same, except to point out that 95 the upstanding lugs 22 are stamped from the material of the cross-head by forming with a suitable tool a depression on one side which forces the material through on the other side, as suggested in my Patent 1,490,- 100 246 granted April 15, 1924, on an application copending herewith.

A feed wire 23 is fixedly attached to the crosshead 20 and is adapted, as hereinafter

explained, to force the lead in the guide tube through the rifled tip 12. It will be noticed in this particular instance, that the entire feed wire is not fixedly attached and extending below the crosshead, but it passes through the crosshead and when the desired length extending upwardly through the crosshead has been reached, that portion of the feed wire passing through the crosshead 10 is soldered thereto, causing these two parts to be firmly attached to each other. The length of the feed wire extending above the crosshead is equal to the distance between the thread 24 in the barrel 10 and the under side of the cap 15. This extension of the feed wire is made necessary to prevent the teeth of the crosshead 20 from becoming disengaged with the threads of the barrel 10. When the cap 17 is turned in a counter-clockwise direction, which in turn revolves the cap 15 to which is soldered the lead magazines 13 and 14, causing the crosshead 16 to move in an upward direction, the feed wire extending above the crosshead will abut the underside of the cap 15 when the teeth 38 in the crosshead has arrived at that point in the barrel where, without the said extension of the feed wire, the tooth of the crosshead would become disengaged from the threads 30 in the barrel 10. As it may be clearly seen, at no time can the operator inadvertently disengage the crosshead from its proper position in the barrel.

Upon further reference to the drawings, especially Fig. 4, it will be observed that the clip 25 consists of a prong 26 and a base or supporting portion 27. The base portion 27 has a flange 28 swaged thereon and said flange is adapted to contact with the inside of the barrel or casing 10. The thick portion of the base 27 is adapted to fit into the hole 19 which is punched in the barrel 10, and the flange 28 prevents the withdrawing of the clip 25 from the barrel 10. In order to hold the clip 25 in the casing, a shell 29 is provided and is adapted to fit inside the casing 10. This shell 29, as may be seen in Fig. 4, when fitted into the barrel 10, will be soldered therein and the lowermost edge of the shell will rest against the shoulder 37 in the barrel.

The clip described briefly above is covered by Patent No. 1,279,186 granted to John C. Wahl and William H. Odum under date 55 of September 17, 1918, and as this clip is not embodied in my invention it is not thought necessary to fully describe the same.

A one-piece guide funnel 32 is inserted in the lower half of the barrel 10. Upon a 60 turning of the cap 17 in a clockwise direction, the crosshead will move downwardly and the feed wire will enter the guide funnel, coming in contact with the lead 33 and causing it to move out through the rifled tip 12 to the required length desired by the

party operating the pencil. The lead guide 32 is funneled as at 39 and the sides 34 fit snugly against the barrel 10 when the lead guide is inserted into the barrel. The lower end of the barrel 10 has a shoulder 35, 70 and that part of the lead guide which is inserted into the swaged portion of the barrel 10 is enlarged as at 36 and is threaded interiorly, said threads being adapted to engage the exterior threads of the rifled tip 12. 75 As will be seen, that part of the lead guide which is enlarged and is threaded interiorly, is beveled in order to fit snugly within the swaged end of the barrel 10. By inserting the rifled tip 12 into the aperture at the 80 swaged end of the barrel 10 and the threads thereof becoming engaged with the threads of the lead guide, it will be seen by a constant turning of the tip in a clockwise direction, it will have a tendency to draw the lead funnel further down into the swaged end of the barrel. This downward pull of the lead guide can be continued until it comes in contact with the shoulder 35 of the barrel 10 which will prevent any further downward 90 movement. This arrangement will cause a locking effect and will tend to hold the rifled tip and lead guide firmly in position.

While I have illustrated and described the preferred form of construction for carrying my invention into effect, this is capable of variation and modification without departure from the spirit of the invention. I, therefore, do not wish to be limited to the precise details of construction set 100 forth, but desire to avail myself of such variations and modifications as come within the scope of the appended claims.

Having described my invention, what I claim as new and desire to secure by Letters 105 Patent is:—

1. In a mechanical pencil, a barrel having internal threads, a lead feeding mechanism comprising a cross-head having threads to engage the threads on the interior of the barrel, a pair of spaced extra lead magazines rotatable together in said barrel to cause rotative and longitudinal movement of said cross-head with relation to said barrel, the inner opposing faces of said magazines being grooved, said cross-head having projections stamped from the body of the cross-head to project from the side faces thereof, said projections slidably fitting in said grooved portions to prevent the cross-head from falling laterally out of the space between the lead magazines when removed from the barrel. 115

2. A mechanical pencil comprising a barrel interiorly threaded for a portion of its 125 length, said threads beginning at a distance spaced inwardly from the open upper end of the barrel, a cap removably mounted on said open end, a cross-head having threaded engagement with the said threads on the in- 130

terior of the barrel, a plunger fixed to said cross-head, and an upstanding rod on the end of the cross-head opposite the plunger, the length of said rod being such that when the threads on the cross-head are nearly unthreaded from the threads on the inside of the barrel, the rod will strike the inner

face of said cap and prevent complete disengagement of said parts without removal of said cap.

In witness whereof I have hereunto subscribed my name.

JOHN C. WAHL.
